UNITED STATES PATENT OFFICE.

ERNST ENDERES, OF ALBERT LEA, MINNESOTA.

DROP HAMMER.

Application filed April 4, 1921. Serial No. 453,215.

To all whom it may concern:

Be it known that I, ERNST ENDERES, a citizen of the United States of America, and resident of Albert Lea, Freeborn County, 5 Minnesota, have invented a new and useful Improvement in Drop Hammers, of which the following is a specification.

The object of this invention is to provide improved means for throwing off or disconnecting the lifting mechanism from a drop hammer.

A further object of this invention is to provide improved means adapted for engagement by a drop hammer in its upward travel for automatically and quickly throwing off or disconnecting the lifting devices from said hammer.

A further object of this invention is to provide means for cushioning the impact of 20 a drop hammer on its upward stroke with throw-off devices.

A further object of this invention is to provide improved means for adjusting the point, in the upward travel of a drop hammer, at which said hammer will engage 25 throw-off devices adapted to disconnect the lifting devices from said hammer.

With these and other objects in view, my invention consists in the construction, arrangement and combination of elements 30 hereinafter set forth, pointed out in my claims and illustrated by the accompanying drawing, in which—

Figure 1 is a front elevation and Figure 2 35 a side elevation of a drop hammer, shown conventionally, and my improvements attached thereto. Figure 3 is a horizontal section on an enlarged scale on the indicated line 3—3 of Figure 2.

For purposes of illustration I have selected from the market a type of drop hammer mechanism and shown the same conventionally as a vehicle for exhibiting my improvements and illustrating their relation 40 to elements now common and well known. In the conventional showing the numerals 10, 11 designate lifting boards, 12, 13 driving pulleys, 14 a lifter frame, 15, 16 left and right uprights respectively, 17 a die holder, 18 an anvil, 19 a hand lever, 20 a stop pin, 21 a lower dog, 22 a hammer, 23 a front lifting roll, 24 a front gear, 25 a front arm, 26 a front lifting rod, 27 a front rod guide and 28 a treadle, all of which elements are common and well known and are adapted from the prior art and machines on the market

and in use; and it is assumed that the construction, purposes and functions of these elements are well established and require no detailed description at this time.

Left and right guides 29, 30, formed with longitudinal T-slots 31, 32 respectively, are mounted vertically and parallel with each other on the front faces of the left and right uprights respectively, the slots therein opening forwardly. Brackets 33, 34 are mounted in contact with and projecting forwardly from the front faces of the guides 29, 30 respectively and are adjustably secured to said guides by bolts 35, 36, having their heads in 60 said slots and extending forwardly therefrom through said brackets. A bar 37, preferably made of wood, is mounted horizontally and connects the brackets 33, 34, end portions of said bar receiving outer end portions of the bolts 35, 36. Washers 36^a are mounted on and fixed to end portions of the bar 37 around the bolts 35, 36, the innermost washers receiving contact of the heads of the brackets 33, 34 with bar 37 and the outermost washers receiving contact and wear of 70 the nuts 36^b on the bolts with bar 37. It is the function of the bolts 35, 36 adjustably to clamp the brackets 33, 34 and bar 37 to the guides 29, 30 so that said bar may be held 75 rigidly at any desired and selected altitude relative to the die holder 17 and also have such relation to the vertical length of the hammer 22. The bar 37 may be adjusted 80 manually as to altitude by loosening and again tightening the bolts 35, 36 and said adjustment is through a wide range governed by the length of the open slots 31, 32 in the guides 29, 30. A stud 38, or stub axle, is adjustably mounted on the front rod 26 by 85 means of a clamp 39 and said clamp may be manually released and tightened and also be adjusted at any desired and selected point on the front rod, there being a relation between the altitudinal adjustment of the stud 90 or stub axle 38 and the altitudinal adjustment of the bar 37. A lever 40 is fulcrumed adjacent its center and is free to oscillate on the stud or stub axle 38. The lever 40 preferably is made of wood. The lever 40 is arranged at right angles to and one end portion thereof extends across the vertical plane of the bar 37 and a keeper 41, or yoke, is mounted on said bar 37 and extends over and encloses loosely three sides of said lever. 100 That end portion of the lever 40 opposite to the bar 37 extends across the vertical path 105 110

of the hammer 22 at one side of the lifting boards 10, 11 and between said lifting boards and the right upright 16. Normally the rear end portion of the lever 40 slightly 5 overbalances the forward portion thereof so that said forward portion engages the yoke 41 and holds the lever substantially in a horizontal plane, (Figure 2), there being a slight freedom of movement between said 10 outer end portion of the lever and the top of the bar 37 as illustrated in Figure 1. A wear plate 42 is mounted on and extends across the top of the bar 37 immediately below the outer end portion of the lever 40 and 15 said wear plate is adapted to contact at times with the lever and save the wooden bar from wear.

It is to be understood that the hammer is 20 lifted by engagement of the front lifting roller 23 and its mate the rear lifting roller, not shown, in the rotation of the geared shafts driven by the pulleys 12, 13, and that said front lifting roller 23 is thrown off or disconnected from the lifting boards 10, 11 25 by upward movement of the arm 25 engaged by the upper end of the front rod 26.

It follows, therefore, that the stroke of the hammer 22 is determined by the distance it is raised from the die holder 17 30 before the throw-off function is applied. Hence adjustment of the stud or stub axle 38 altitudinally on the front rod 26 and a corresponding adjustment of the bar 37 altitudinally locates, governs and determines 35 the point of contact of the hammer 22 with the inner end portion of the lever 40. When the hammer 22, in its upward travel, contacts with the inner end portion of the lever 40 it oscillates said lever so that 40 the forward end portion thereof contacts with the bar 37 through the medium of the interposed wear plate 42. Further oscillation of the lever 40 being stopped by contact with the bar 37 the front rod 26 is 45 raised through the medium of the stub axle 38 and clamp 39 acted upon by the central portion of the lever 40. Such raising of the front rod 26 lifts the arm 25 and disconnects the front roller 23 from the lifting 50 boards 10, 11. The contact of the hammer 22 with the lever 40 is by impact and is forcible and speedy and the reaction of such impact through said lever, the bar 37, stub axle 38 and clamp 39 is substantially immediate, prompt and very quick to the end of 55 raising the front rod 26 and arm 25 and throwing off the front roller practically instantaneously with said impact. Herein lies the desirability and advantage of making 60 the bar 37 and lever 40 of wood in that the impact of the hammer with the lever and the reaction of the lever on the bar is cushioned, tempered and softened. Utilizing wood for the lever and bar avoids and minimizes 65 shock on all of the parts susceptible

of receiving any reaction whatever from such impact. Experiment with a machine equipped with the attachments herein illustrated and described have shown that the use of the wooden members indefinitely extends the period of usefulness and indefinitely and to a large extent minimizes the necessity of replacement and repairs in those parts receiving the impact directly or by reaction.

When it is desired to change the stroke of the hammer 22 the bar 37 and stud or stub axle 38 are proportionately adjusted altitudinally, said elements coacting to determine the range of such stroke through 75 the interrelation therewith of the lever 40.

Except as above pointed out, modified and varied by the use and operation of the attachments specifically described, the construction, operation and use of the other 80 elements illustrated and any other elements necessary and not illustrated, are the same as at present.

I claim as my invention—

1. In a drop hammer provided with spaced 90 uprights, a hammer adapted for reciprocation between said uprights, lifting boards carried by the hammer and lifting devices adapted to act on said lifting boards at times; the combination with said hammer 95 and lifting devices of a wooden bar vertically adjustably mounted on said uprights, a tripping rod acting on said lifting devices, and a lever carried by said tripping rod and extending across the plane of and adapted to 100 engage said bar and also extending across the path of and adapted to be engaged by said hammer in its upward movement.

2. In a drop hammer provided with spaced 105 uprights, a hammer adapted for reciprocation between said uprights, lifting boards at times carried by the hammer and lifting devices adapted to act on said lifting boards, the combination with said hammer and lifting devices of a wooden bar vertically 110 adjustably mounted on said uprights, a tripping rod acting on said lifting devices, and a wooden lever carried by said tripping rod and extending across the path of and adapted to engage said bar and also extending across the path of and adapted to be engaged 115 by said hammer in its upward movement.

3. In a drop hammer provided with spaced 120 uprights, a hammer adapted for reciprocation between said uprights; lifting devices adapted to raise said hammer, and throw-off devices adapted to suspend the lifting devices, the combination with said hammer and throw-off devices of a wooden bar vertically 125 adjustably mounted on said uprights, said throw-off devices comprising a tripping rod acting on said lifting devices, a wooden lever carried by said tripping rod and extending across the plane of and adapted to engage said bar and also extending across the path 130

of and adapted to be engaged by said hammer in its upward movement, and a wear plate on said bar adapted to contact with the lever.

5 4. In a drop hammer mechanism having spaced uprights, a hammer adapted for reciprocation between them, lifting devices adapted to raise said hammer and throw-off devices adapted to suspend the lifting devices, the combination with said hammer and throw-off devices of spaced parallel guides formed with T-slots mounted on said uprights, brackets adjustably mounted on said guides, a wooden bar connecting said brackets and extending across the path of travel of the hammer, bolts extending through said brackets and bar and having their heads within said T-slots, and a wooden lever carried by said throw-off devices and extending at its ends across and above the hammer and bar, respectively, whereby engagement of the hammer with one end of said lever and engagement of the other end of said lever with said bar reacts on and operates said lifting devices.

5. In a drop hammer, the combination with the hammer, means for lifting the same and a front lifting rod adapted to act on the lifting means at times, of vertical guides, a wooden bar connecting and adjustable altitudinally on said guides, and a wooden lever fulcrumed on and adjustable altitudinally relative to said front lifting rod, said lever extending across and above the hammer and bar and adapted to be engaged by the hammer and to engage the bar to the end of raising said front lifting rod.

6. In a drop hammer, the combination with the hammer, means for lifting the same and a front lifting rod adapted to act on

the lifting means at times, of vertical guides, a wooden bar connecting and adjustable altitudinally on said guides, a keeper on said bar, a stub axle on and adjustable vertically of said rod, a wooden lever fulcrumed on and adjustable altitudinally with said stub axle, said lever extending across and above the hammer and bar and adapted to be engaged by said hammer and to engage said keeper and bar to the end of raising said front lifting rod, said keeper or yoke being spaced from said bar a distance greater than the vertical width of and loosely embracing, the crossing portion of the lever.

7. In a drop hammer, the combination with the hammer, lifting means therefor, and a front lifting rod adapted to act on the lifting means at times, of vertical guides, a wooden bar connecting and adjustable altitudinally on said guides, a wooden lever fulcrumed adjacent its center on and adjustable altitudinally relative to said front lifting rod, said lever extending across and above the hammer at one end and above and across the bar at the other end and adapted to be engaged by said hammer and to engage said bar to the end of raising said front lifting rod, a keeper or yoke carried by said bar and spaced therefrom and adapted loosely to embrace the crossing portion of said lever, and a wear plate on said bar within the yoke and adapted to receive the impact of the lever, there being a range of movement of the lever end between the keeper and wear plate.

Signed at Des Moines, in the county of Polk and State of Iowa, this 16th day of March, 1921.

ERNST ENDERES.
